UNITED STATES PATENT OFFICE

HOWARD B. SHERMAN AND DONALD P. ORDWAY, OF BATTLE CREEK, MICHIGAN, ASSIGNEES TO AMERICAN STAMPING CO., OF BATTLE CREEK, MICHIGAN, A CORPORATION OF MICHIGAN

COMBINATION HOLDER FOR RAZOR BLADES AND PAPER

Application filed September 17, 1925. Serial No. 56,946.

This invention is a novel combination holder for used safety razor blades and paper for wiping such blades, and its object is to provide a novel and convenient device for holding paper wipers for razor blades, or toilet paper, and a receptacle for used safety razor blades wherein they will be kept out of the way of children or others who might be injured thereby.

10 The accompanying drawings illustrate a practical embodiment of the invention, and we will describe the same with reference thereto, and summarize in the claims the novel features of construction and novel 15 combinations of parts for which protection is desired.

In said drawings:

Figure 1 is a front view of the combination holder in position for use.

20 Figure 2 is a perspective rear view of the cover of such holder, defached.

Figure 3 is a perspective view of the casing of such holder with cover removed.

25 Figure 4 is a vertical sectional view of the holder in operative position in a wall.

As shown in the drawings the holder comprises a hollow member or casing closed at front and preferably having an internal paper compartment and a used blade receiver compartment; a closure for the casing and compartment; and a used blade receiver as hereinafter explained. The several parts may be made of any suitable material, but in the particular form shown the parts 30 are supposed to be cast or molded; although they may also be made of sheet metal.

The combination holder as shown in the drawings is especially useful for so called "built-in" work; and comprises a rectangular casing 10, being preferably closed at rear, top, bottom and ends but open at the front, said casing being adapted to be set into a wall S, of a room or the like, with the open side outermost, and flush with the exterior 40 surface of the wall. The interior of the casing 10 is preferably divided by a vertical partition 10a into a large compartment A adapted to contain paper wiper sheets W, and a smaller compartment B adapted to 45 contain used blades.

The closure 11 may be also cast and of such size as to neatly close the opening in the front of the casing 10, and is shown as provided with flanges 11d to overlap and cover the outer edges of the top, bottom and end walls of the 55 casing.

The cover may be detachably attached to the casing 10 by any desirable means; in the particular construction illustrated in the drawings the closure 11 is provided at its opposite ends with pins 11e which are adapted to engage arcuate slots 10b in the inner surface of the end walls of the casing 10; when the closure is properly positioned the pins 11e enter the arcuate slots 10b and draw the 60 closure 11 towards the casing 10 and retain closure in place. The closure 11 can be removed by inserting the fingers in slot 11a and lifting the closure until the pins 11e are disengaged from slots 10b.

70 This closure 11 is provided with a slot 11a through which paper wipers may be removed from the compartment A; and with a small slot 11b above and to one side of the slot 11a, through which used razor blades may be inserted into the compartment B, or into a suitable blade receiver in said compartment.

75 In the construction shown a blade receiver 11c is attached to or preferably molded on the inner face of the closure 11 beneath the slot 11b, so that the used razor blades inserted through slot 11b will fall into the receiver 11c and be retained therein.

The receiver 11c might in some instances be made separate from the closure 11, and detachably attached thereto or removably placed within the blade compartment B. The construction shown is the simplest and the at present preferred form. When it is desired to empty the used blades the closure 11 80 can be removed, thereby removing the used blade receiver with it, and the used blades can be emptied where it may be desired to finally dispose of them.

We claim:

1. A holder for used razor blades comprising a hollow casing adapted for insertion in a wall pocket and open at the front side; a plate forming a closure for the open front side of the casing, and provided with a blade receiv- 90 95 100

ing slot; a blade receiver attached to the said closure plate beneath the said blade receiving slot, and means for securing the closure plate to the casing.

5 2. A holder for used razor blades comprising a hollow casing open at the front side, and having arcuate slots in its end portions; a plate forming a closure for the open front side of the casing having lugs on its ends detachably engaging said arcuate slots and having a blade receiving slot; and a blade receiver attached to the said closure plate beneath the said blade receiving slot.

10 In testimony that we claim the foregoing as our own, we affix our signatures.

15 HOWARD B. SHERMAN.

DONALD P. ORDWAY.
